CLAIM

The ornamental design for a seat, as shown and described.

DESCRIPTION

FIG. 1 is a perspective view of a seat showing our new design in the form of a sofa thereof;

FIG. 2 is a front elevational view;

FIG. 3 is a top plan view;

FIG. 4 is a right side elevational view, and the left side elevational view being a mirror image thereof;

FIG. 5 is a rear perspective view of FIG. 1;

FIG. 6 is a perspective view of a seat of furniture showing our new design in the form of a sectional thereof;

FIG. 7 is a top plan view of FIG. 6;

FIG. 8 is a left side elevational view of FIG. 6;

FIG. 9 is a right side elevational view of FIG. 6;

FIG. 10 is a left rear perspective view of FIG. 6; and,

FIG. 11 is a right rear perspective view of FIG. 6.
